Patented May 21, 1901.

J. S. BANCROFT.
PAPER FEED MECHANISM.

(Application filed Sept. 25, 1900.)

(No Model.)

UNITED STATES PATENT OFFICE.

JOHN SELLERS BANCROFT, OF PHILADELPHIA, PENNSYLVANIA, ASSIGNOR
TO THE LANSTON MONOTYPE MACHINE COMPANY, OF WASHINGTON,
DISTRICT OF COLUMBIA.

PAPER-FEED MECHANISM.

SPECIFICATION forming part of Letters Patent No. 674,362, dated May 21, 1901.

Application filed September 25, 1900. Serial No. 81,011. (No model.)

To all whom it may concern:

Be it known that I, JOHN SELLERS BANCROFT, a citizen of the United States, residing at Philadelphia, in the county of Philadelphia and State of Pennsylvania, have invented certain new and useful Improvements in Paper-Feed Mechanism; and I do hereby declare the following to be a full, clear, and exact description of the same, reference being had to the accompanying drawings, forming a part of this specification, and to the figures of reference marked thereon.

This invention relates to paper-feed mechanism such as is employed in connection with type casting and composing machines for intermittently advancing a perforated record-strip, the latter controlling the admission of air or other fluid under pressure to a series of ports communicating with the various controllable elements of the machine; and it comprises improvements in the arrangement and disposition of the supply-pipe through which air is delivered to the air-bar, whereby unnecessary movements of the supply-pipe are suppressed and the air-bar is permitted to be swung back to uncover the cross-bar with which it co-operates. This is accomplished by attaching the supply-pipe to a coupling coincident with the axis about which the air-bar vibrates.

It also consists in a novel and improved form of actuating mechanism applied to the ratchet-wheel of the paper-feed device for intermittently advancing the latter, said mechanism including as its principal features a retaining and an actuating pawl so connected and operated that each shall be moved to its seat between the ratchet-teeth without sliding thereon or changing the position of the feeding devices before the other is withdrawn from its seat, whereby the wear upon the ratchet-wheel and pawls is prevented and the action of the feed rendered more certain and positive. Incidentally this feature also includes the connecting of the two pawls in such manner that each shall in turn constitute the pivotal support through which motion is transmitted to the opposite pawl from the actuating devices both in approaching and receding from the ratchet-wheel, so that one

pawl will remain fully seated while the other is being withdrawn and will retain its seat until the opposite pawl is in turn fully seated preliminary to the withdrawal of the first-mentioned pawl.

It also comprises minor novel features pertaining to the actuating devices, all as hereinafter more fully described, and pointed out in the claims.

In the accompanying drawings, illustrating the preferred embodiment of the said invention, Figure 1 is an end view, and Fig. 2 is a front elevation, partly in section, of an organized feeding mechanism embodying the improvements. Fig. 3 is a detail showing the connections between the actuating and feeding pawls. Figs. 4 and 5 are diagrammatic views showing the pawls in different relative positions when in action. Fig. 6 is a detail view, partly in section, showing the pawl-actuating connection. Fig. 7 is a detail showing the locking-seat for the pawl connection.

Like numerals of reference in the several figures indicate the same parts.

In its general construction the paper-feed mechanism with which the present improvements are shown embodied is that of Patent No. 625,998, to which reference may be had for a more complete description of its general operation. It will suffice for present purposes to designate and identify certain of its component parts, as follows: 1, the frame; 2, the cross-bar, containing the series of ports leading to the various actuating devices; 3, the pin-wheels, attached to shaft 4, journaled in the cross-bar; 5, the ratchet-wheel, secured to shaft 4; 6, the air-bar, provided with arms 7, mounted loosely upon shaft 8; 9, sleeve on shaft 8, provided with two arms 10, each connected to one end of the air-bar through bolt 11 and spring 12; 13, valve controlling the admission of air to the air-bar and operated upon by one of the arms 10 when the latter is depressed to bring the air-bar into contact with the surface of the record-strip; 14, the pulley for actuating the winding-spool; 15, bearings for the supply-spool; 16, driving-pulley on shaft 4 for actuating the winding-spool; 17, elastic belt for communicating motion from driving-pulley 16 to pulley 14, and

18 lever receiving motion from the actuating devices through connecting-rod 19.

Instead of connecting the air-supply pipe 20 directly to the air-bar 6, as heretofore, 5 said pipe is connected to a coupling 21, concentric with and supported upon the extension of shaft 8, constituting the axis of the air-bar and its levers 10. The interior of this sleeve 21 communicates, through a passage 22, formed in one end of shaft 8, with a passage formed in one arm 7 of the air-bar, leading to the chamber below the valve, as shown in Fig. 2. By thus attaching the supply-pipe to the axis about which the air-bar 15 turns it is not only possible to make the supply-pipe rigid, but it greatly facilitates access being had to the cross-bar, as the air-bar can be swung back to uncover it without disturbing the connection with the supply-pipe.

20 The connection, Fig. 6, through which motion is transmitted from lever 18 to the air-bar comprises a slotted link 25, adjustably attached to one end of the rod 26, whose opposite end is similarly attached to a head 27, 25 slotted laterally for the reception of a pin 28 on lever 10. The rod 26 passes through a slotted bearing 29 on the frame and is surrounded below said bearing by a sleeve 30, which serves to limit the vertical motion of 30 the connection and of the air-bar when attached thereto. Upon the upper face of bearing 29 are provided two depressions or seats 31, such as are formed by two intersecting circular recesses, thereby producing two opposite shoulders 32 intermediate the seats, as 35 illustrated in Fig. 7. Fitted loosely within the elongated aperture in bearing 29 is a headed sleeve 33, and between the latter and the head 27 is arranged a spring 34, surrounding the rod 26. This spring 34 serves to elevate the air-bar, the lever 18 operating in opposition thereto to depress the air-bar and seat it upon the record-strip and cross-bar. Said spring also serves, in conjunction with 40 sleeve 33, to retain the connection at either extreme of the slot in bearing 29, and when in one position the connection will be in engagement with the air-bar, and when in the other it will be disconnected therefrom and 45 the air-bar will be released, so that it can be turned back. To engage or disengage the connection, it is only necessary to push it laterally, the spring 34 yielding as the head of the sleeve passes from one seat to the other. 50 It will be seen that the sleeve 30 not only serves to limit the elevation of the air-bar when in action, but also to retain the connection in position when disconnected from the air-bar.

55 The driving of the supply-spool through the medium of the elastic belt has the effect of producing unequal tension in the belt, so that at the end of the feeding movement there is manifested a slight tendency on the part 60 of the shaft 4, carrying the pin-wheels, to turn in its bearings as the pawls are shifted, and the movements of the pawls being syn-

chronous it results that as one pawl leaves the ratchet-wheel and the other enters the ratchet-wheel will follow these movements, 70 thereby causing the engaging ends of the pawls to rub with more or less friction against the sides of the teeth, gradually wearing the latter, and thereby disturbing the accurate positioning of the record-strip with relation 75 to the air-ports. To overcome this, provision has been made whereby each pawl after being seated in the ratchet-wheel shall retain its position while the other pawl is being withdrawn and until it is again engaged and firmly seated. 80 As in the prior patent mentioned, the holding-pawl 40 is pivotally supported upon the frame, while the actuating-pawl 41 is mounted upon the annulus 42, the latter being supported to move in a path concentric with the axis of 85 the shaft 4 and provided with a lug 43, movable between adjustable stops on the frame; but unlike the said prior structure the outer end of the holding-pawl 40 is pivotally attached to one end of a link or lever 44, the 90 opposite or outer end of said link being pivotally attached to the upper end of an elastic connection or link 45, whose lower end is pivotally attached to lever 18. At a point intermediate the holding-pawl 40 and the actuating-link 45 a link 46 is pivotally attached to the link 44, the lower end of said link 46 being pivotally connected to an arm on the actuating-pawl 41 in rear of its pivot. A spring 47 is interposed between the free or engaging 95 ends of holding-pawl 40 and actuating-pawl 41. A stop 48 is located upon the annulus 42 in position to limit the outward motion of the actuating-pawl, and in rear of the holding-pawl 40 a similar stop is mounted upon the 100 frame; but in the latter case this stop, formed by lever 49, is adjustable and constitutes a means for locking the feed mechanism against motion when desired. This effect is produced when the lever 49 is turned down to engage 105 the holding-pawl, and thus prevent its withdrawal from the ratchet-wheel, under which circumstances the movements of the lever 18 will be accommodated by the elastic connection 45. The relative motions of the actuating and holding pawls as thus arranged and 110 connected will be best understood by a comparison of Figs. 1, 4, and 5. The position which the pawls assume at the commencement of the stroke of the driving connection 45 in 115 either direction is represented in Fig. 4. Fig. 5 represents the feeding motion, and Fig. 1 the return motion. During the upward or return motion of the actuating-pawl the holding-pawl 40 is seated in the ratchet-wheel and furnishes the fulcrum about which link 44 turns in withdrawing the actuating-pawl 41 until it contacts with its stop-pin, after which the movement is communicated to the support upon which said pawl is mounted—to wit, the annulus 42—and the latter is turned until it contacts with the left-hand stop, as indicated in Fig. 1, thus completing the return 120 movement of the actuating-pawl and at the 125

same time retaining control of the ratchet-wheel through the holding-pawl. This position is maintained and the feeding devices held locked in position until the driving connection is drawn down or advanced in the direction of the feed movement. At the beginning of this motion the outer end of link 44 is moved in a direction tending to withdraw the holding-pawl and engage the actuating-pawl, which movements might be accomplished simultaneously or successively were it not for the presence of spring 47, whose action coincides with the movement of the actuating-pawl and is opposed to that of the holding-pawl. Hence the latter is caused to remain in engagement with the ratchet-wheel while the actuating-pawl moves into engagement therewith, as represented in Fig. 4. During this movement the holding-pawl furnishes the fulcrum for link 44; but as soon as the actuating-pawl becomes seated in the ratchet-wheel the conditions are reversed, the actuating-pawl being arrested, so that the continued movement of link 44 will elevate or withdraw the holding-pawl until arrested by its stop, as indicated in Fig. 5, the actuating-pawl now furnishing the fulcrum. As soon as the holding-pawl has been elevated into contact with its stop it again becomes the fulcrum about which link 44 turns, and the actuating-pawl is advanced, carrying with it the ratchet-wheel and devices connected therewith. The feeding motion having been completed and the movement of the connection 45 reversed, the first action is to seat the holding-pawl, (the actuating-pawl supplying the fulcrum for this movement of link 44,) then withdraw the actuating-pawl (the holding-pawl furnishing the fulcrum for this movement of link 44) until the actuating-pawl engages its stop, when the further movement of the connection 45 will retract the actuating-pawl and its support to the position as indicated in Fig. 1 preliminary to the next feeding movement. It will be seen that as thus arranged either one or the other of the two pawls are at all times not only in engagement with the teeth of the ratchet-wheel, but firmly seated therein in position to hold said wheel against motion in either direction until the opposite pawl is in like manner fully seated, so that there can be no lost motion or slipping of one part upon another either in transferring the control of the ratchet-wheel from one pawl to the other or while effecting the feed motion, it being of course understood that the engaging ends of the pawls are properly shaped to accurately enter and fit between the teeth of the ratchet-wheel when seated and to withdraw freely without friction when retracted.

By reference to Fig. 4 it will be seen that spring 47 tends at all times to hold both pawls in engagement with the ratchet-wheel, so that when either pawl is withdrawn the first motion of the connection 45 in a direction to seat the disengaged pawl will coincide

with the action of the spring. Thus, as shown in Fig. 1, the spring is operating in a direction to throw the actuating-pawl into engagement, and a downward pull upon the connection 45 operates in the same direction, and the same is true of Fig. 5, wherein the holding-pawl is shown withdrawn instead of the actuating-pawl, and the stress of spring 47 is in a direction to seat the holding-pawl, which coincides with the movement imparted to the latter when connection 45 is elevated. Hence it will be seen that the seating of the pawls is accomplished without developing sufficient pressure to disturb the support of the actuating-pawl and that the seating once having been effected the action is positive in withdrawing the opposite pawl and shifting the support of the actuating-pawl. 85

Having thus described my invention, what I claim as new, and desire to secure by Letters Patent, is—

1. In a paper-feed mechanism such as described, the combination with the air-bar supported to oscillate about an axis, of a supply-pipe in line with said axis and communicating with the air-bar through its supporting-arm as and for the purpose set forth. 90

2. In a feeding mechanism, such as described, the combination with the pivoted air-bar and axially-connected supply-pipe, of an actuating connection provided with a spring for elevating or retracting the air-bar said connection being detachably connected to the air-bar devices, to permit the air-bar to be swung back to uncover the cross-bar as set forth. 95

3. In a feed mechanism such as described, the combination with the air-bar and the actuating-lever therefor, of a connection or link provided with a spring and a stop for limiting its movements in one direction, said connection or link being meditately attached to the air-bar through a detachable connection, 105 as set forth. 110

4. In a paper-feed mechanism such as described, the combination with a driving-arm as 18 and a driven arm as 10, of a connection intermediate said arms and extending through 115 a relatively-fixed bearing or guide provided with contiguous seats, a sleeve adapted to engage either of said seats and be shifted from one to the other, and a spring intermediate said sleeve and a shoulder or head on 120 the connection; substantially as described. 115

5. The combination with actuating-arm 18, of the air-bar driving connection projecting through a bearing on the frame and provided at one end with an open link and at the opposite end with a slotted head, a limiting sleeve or gage intermediate the bearing and the open link, an actuating-spring intermediate said bearing and the slotted head, and a headed or flanged sleeve adapted to engage 125 either of two seats in the fixed bearing and held to position by said actuating-spring, as and for the purpose set forth. 130

6. In an actuating mechanism for paper-

feed and similar devices the combination of the following elements, to wit; a ratchet-wheel; a locking or holding pawl movable into and out of engagement with the ratchet-wheel; an actuating-pawl movable into and out of engagement with the ratchet-wheel and mounted to vibrate both with the latter and in the opposite direction; a main driver; and actuating devices intermediate the main driver and the holding and actuating pawls for alternately seating and withdrawing each of the latter, said devices actuating the pawls successively and maintaining each pawl immovably in its seat on the ratchet-wheel during the seating or withdrawal of the opposite pawl; substantially as described.

7. In an intermitting driving mechanism, such as described, the combination with the ratchet-wheel, the holding-pawl and the actuating-pawl, of a main driver connected to both of said pawls through a lever system wherein each pawl becomes the fulcrum for the seating or unseating of the opposite pawl; substantially as described.

25 8. In an intermitting driving mechanism such as described, the combination with the ratchet-wheel, the holding-pawl and the actuating-pawl, the latter mounted upon a movable support, of a link or lever pivotally connected to both pawls and to the main driver, and a spring operating in a direction to effect the engagement of both pawls with the

ratchet-wheel, as and for the purpose set forth.

9. In an intermitting driving or feed mechanism such as described, the combination with the ratchet-wheel, the holding-pawl mounted upon a fixed support and the actuating-pawl mounted upon a movable support, of a back-stop for the holding-pawl, a back-stop for the actuating-pawl, a spring connecting the engaging ends of the two pawls and a link or lever pivoted at one end to the holding-pawl, at the opposite end to the driving mechanism, and at an intermediate point to the actuating-pawl through a flexible connection such as a link; substantially as described.

10. In an intermitting driving or feed mechanism such as described, the combination with the ratchet-wheel, the holding-pawl and the actuating-pawl, the latter mounted upon a movable support, of a spring intermediate the free or engaging ends of both pawls, and a lever or link connected at opposite ends to the main driver and the free or engaging end of the holding-link, respectively, and at an intermediate point connected by a link with the actuating-pawl in rear of its pivot; substantially as described.
